UNITED STATES PATENT OFFICE.

WILLIAM HENRY SAUVAGE, OF NEW YORK, N. Y., ASSIGNOR TO SAUVAGE
SAFETY BRAKE COMPANY, A CORPORATION OF NEW JERSEY.

FLUID-PRESSURE BRAKE.

No. 825,077.

Specification of Letters Patent.

Patented July 3, 1906.

Application filed December 26, 1905. Serial No. 293,160.

To all whom it may concern:

Be it known that I, WILLIAM HENRY SAUVAGE, a citizen of the United States of America, and a resident of the borough of Manhattan, city, county, and State of New York, have invented certain new and useful Improvements in Fluid - Pressure Brakes, of which the following is a specification.

My invention relates, generally, to fluid-pressure brake systems, and more specifically comprises an apparatus whereby a second or auxiliary cylinder may operate its piston to reinforce or increase the brake-pressure after the main cylinder has operated its piston to take up the slack and set the brake-shoes against the wheels with an initial pressure of less degree. Heretofore it has been proposed to accomplish this result by means of an arrangement of two cylinders side by side or otherwise arranged parallel to one another and both exerting their braking stress in the same direction, the two piston-rods being connected by suitable systems of levers.

My present invention avoids the use of such additional lever systems and in its preferred form removes all strain from the fastening-bolts which hold the cylinders to the car-body, placing the two cylinders between the two levers of the present standard brake-rigging back to back, so that the braking force is all transmitted to a floating-lever system, as in the present one-cylinder arrangement, in which the second brake-lever is pivoted to the back head of the cylinder.

My invention possesses other advantages which will hereinafter be pointed out.

The best form of apparatus at present known to me embodying my invention, together with certain modifications thereof, is illustrated in the accompanying two sheets of drawings, in which—

Figure 1 is a plan view of the brake-cylinders and part of the brake-rigging with my invention applied thereto. Fig. 2 is a modification thereof, showing a ratchet mechanism. Fig. 3 is a modification showing a different arrangement of air-passages in which the special form of valve shown in Fig. 4 may be used. Fig. 4 shows an enlarged detail of such valve in cross-section; and Fig. 5 shows a modification in which a clutch released by the triple-valve exhaust is used, together with a system of levers for multi-

plying the braking force, the two brake-cylinders being of the same cross-sectional area 55 in this modification.

Throughout the drawings, like reference-figures indicate like parts.

1 is the main brake-cylinder, 2 its piston, and 3 the piston-rod pivoted to brake-lever 4 6c of usual construction.

5 is a second brake-cylinder of larger cross-section placed back to back with cylinder 1, provided with its piston 6 and piston-rod 7, which is pivoted to the other brake-lever 8. 65 The two brake-levers are connected together by the usual tie-rod 9.

10 is the auxiliary reservoir; 11, the train-pipe; 12, the ordinary triple valve, and 13 the pipe connecting said triple valve with the 70 interior of cylinder 1. The passage-way 14 is bored out through the boss 15 on cylinder 1 and extends to the interior of the cylinder 5. Communication from this passage-way to the interior of cylinder 1 is afforded by 75 the hole 17, bored from the exterior of the cylinder and closed at its outer end by the plug 18.

19 is the usual form of friction clutch-dog, pivoted to the main cylinder at 20 and having 80 a perforation through which the piston-rod 3 extends.

21 is a tension-spring normally pulling a dog 19 to the left, so as to clutch the piston-rod 3, and 22 is a rod carried by an arm 23, 85 fixed to the piston-rod 7. This rod 22 is provided with an adjustable tappet-block 24, which when piston 6 is at the extreme right of its travel will strike clutch-dog 19 and trip the clutch.

In Fig. 2 a pawl 19^a is substituted for clutch-dog 19, and this engages with ratchet-tooth 3^a on piston-rod 3. Otherwise the construction is the same.

In the modification shown in Fig. 3 an external system of piping 15^a takes the place of the bored-out boss 15 (shown in Fig. 1) and communicates with the cylinder 1 through the port 17^a. In this system of piping is preferably located a valve 16. (Shown in detail in Fig. 4.) Such valve has the plunger 25 normally held down by the spring 26 and closing the passage of air from cylinder 1 to cylinder 5 until a sufficient pressure is attained to overpower said spring 26 and lift the valve-plunger 25. 27 is a piston connected to said

valve-plunger 25, working in the upper portion of the casing 28. 29 is a downwardly-opening check-valve and is normally held closed by spring 30.

- 5 In the modification shown in Fig. 5 the second cylinder 5 is of the same cross-sectional area as the first cylinder 1, and to attain the added brake force piston-rod 7 is connected to the brake-lever 8 by means of 10 an intermediate lever system, comprising the lever 31, pivoted loosely to the car-body at 32 and connected by link 33 to one end of lever 8. 34 is a guide frame or strip attached to the car-body coöperating with pin 35 on lever 15 8 to insure movement of the lever 8 substantially parallel to piston-rod 7. The piston-rod 3 has an extension 36, which passes through the clutch-dog 19^b, pivoted at 20^b to the car-body. 37 is a pneumatic cylinder 20 connected by pipe 38 to the exhaust-port of triple valve 12. This cylinder has a piston 39, operated by spring 40, the piston-rod 41 being connected to the clutch-dog 19^b. 42 is an exhaust-port. 43 is an ordinary cut-out 25 valve controlling the connection between the two cylinders 1 and 5.

Such being the construction, the mode of operation of my invention is as follows: When the air-brakes are applied, air is admitted 30 to the main cylinder 1, and piston 2 is forced to the right, taking up the brake-shoe clearance and slack of the rigging and setting the brakes with their initial pressure. When the movement of the piston 2 has accomplished 35 this, it has uncovered the opening 17 in the wall of the cylinder, and the air passes over through the passage-way 14 to the second cylinder 5. This forces piston 6 to the left, and as the area of said piston is greater than that 40 of piston 2 it drives the piston-rod 7 out with greater force than the air in the cylinder 1 can exert upon piston 2, with the result that the floating-brake-lever system tends to shift to the left; but this movement, so far as the 45 piston-rod 3 is concerned, is immediately checked by the friction-dog 19 clutching the same. The subsequently-applied power of compressed air is transmitted to the brake-rigging by the continued movement of piston 50 6 to the left. When the brakes are released, the air first goes out of cylinder 5, allowing piston 6 to move to the right until it reaches the extreme limit of motion by striking against the back of the cylinder 5. This motion is sufficient to cause the tappet-block 24 on rod 22 to strike the end of clutch-dog 19 and force the same into a position which will trip its clutching action on the piston-rod 3. Piston 2 is thus allowed to travel back to- 55 ward the left as the air continues to escape from the interior to the cylinder 1, and the brakes are released.

The operation of the modification shown in Fig. 2 is the same, except that piston 3 is held

by the pawl 19^a, engaging the ratchet 34, 65 which pawl is tripped by the tappet-block 24 striking the bell-crank lever 44.

The operation of the modification shown in Figs. 3 and 4 is as before described, except that in cases where excessive brake-shoe clearance 70 exists or the brake-rigging springs and permits lost motion to occur the air will not pass over from cylinder 1 to cylinder 5 as soon as the port 17^a is opened by reason of the continued closure of the valve 16. When, however, all 75 lost motion has been taken up and the predetermined brake-pressure applied, then spring 26 will be overpowered, the plunger 25 will rise, the air will pass through into the chamber 28 and acting upon piston 27 hold the 80 valve open, thus permitting free passage of air from cylinder 1 to cylinder 5. When the brakes are released, the check-valve 29 will open whenever valve 25 closes and permit the exhaustion of all air from cylinder 5 back 85 to cylinder 1.

In the modification shown in Fig. 5 the operation is the same, except that the added force tending to shift the brake-lever system to the left is secured with the use of a cylinder 90 5 of the same size as cylinder 1 through the agency of the multiplying-lever 31 and link 33. The backward motion of piston 2 is prevented by the action of the clutch-dog 19^b, and said clutch is tripped when the brakes 95 are released by the power of the exhaust-air escaping from the triple valve 12, which forces the piston 39 in cylinder 37 to the right until the exhaust-port 42 is opened. When all the air has been exhausted from the brake-cylinders, the spring 40 forces the piston to the left, resetting the clutch. It is evident that the same resulting brake power may be attained with the proportions of lever shown in Fig. 5 from a cylinder of given cross-section as would 100 be attained from a cylinder of double the cross-section in the arrangement shown in Figs. 1 and 3.

The advantages of my invention comprise the compact arrangement, the removal of all 110 stress from the fastenings by which the brake-cylinders are held to the car-body, and the economy in the use of the fluid under pressure, which results. Thus cylinder 1 may be made of small diameter just sufficient to exert the power required to take up the brake-shoe clearance. Such cylinder might be made as low as four or five inches in diameter in extreme cases. The cylinder 5, however, could be made of very great diameter— 115 say fourteen or sixteen inches—and a great ultimate braking power is secured with a small consumption of air, because the slack of the rigging having been all taken up force applied to piston 6 would be immediately 120 transformed into brake-shoe pressure without any considerable travel of such piston. In the same way this greater power could be 125

attained in the construction shown in Fig. 5 by multiplying-levers 31 or the equivalent arrangement with the use of a small and consequently cheaper cylinder 5. The arrangement shown in Fig. 5 would render it possible to standardize all brake-cylinders on all cars of every weight and description, the variations in the braking power being secured merely by variation of the multiplying-lever system 31.

It is evident, of course, that various changes could be made in the details of construction illustrated without departing from the spirit and scope of my invention. Other forms of friction tension ratchets and latches could be substituted for those shown, and the air-ports and passage-ways and valves could be modified in various manners. These and similar modifications, however, I should still consider within the boundaries of my invention.

Having therefore described my invention, I claim—

1. In a fluid-pressure brake system, the combination with the main cylinder, its piston and piston-rod, brake-rigging and triple valve, of a second brake-cylinder, its piston and piston-rod, and an air-passage extending to the second cylinder from a port in the side 25 of the first cylinder at a point some distance from the cylinder-head, said cylinders being arranged back to back and their respective piston-rods being connected to the adjacent brake-levers.

2. In a fluid-pressure brake system, the combination with the main cylinder, its piston and piston-rod, brake-rigging and triple valve, of a second brake-cylinder, its piston and piston-rod, and means for admitting 30 fluid under pressure to the second cylinder after the movement of the piston in the main cylinder has begun, said cylinders being arranged back to back and their respective piston-rods being connected to the adjacent 35 brake-levers, together with means for locking the piston of the main cylinder against backward movement while the piston of the second cylinder is on its outstroke.

3. In a fluid-pressure brake system, the combination with the main cylinder, its piston and piston-rod, brake-rigging and triple valve, of a second brake-cylinder, its piston and piston-rod, and means for admitting 40 fluid under pressure to the second cylinder after the movement of the piston in the main cylinder has begun, said cylinders being arranged back to back and their respective piston-rods being connected to the adjacent 45 brake-levers, together with means for locking the piston of the main cylinder against backward movement while the piston of the second cylinder is on its outstroke, and for 50 unlocking it during release of the brakes.

4. In a fluid-pressure brake system, the combination with the main cylinder, its piston and piston-rod, brake-rigging and triple valve, of a second brake-cylinder, its piston and piston-rod, and an air-passage extending to the second cylinder from a port in the side 55 of the first cylinder at a point some distance from the cylinder-head, said cylinders being arranged back to back and their respective piston-rods being connected to the adjacent 60 brake-levers, said second cylinder being of larger cross-section than the first cylinder.

5. In a fluid-pressure brake system, the combination with the main cylinder, its piston and piston-rod, brake-rigging and triple valve, of a second brake-cylinder, its piston and piston-rod, and means for admitting 65 fluid under pressure to the second cylinder after the movement of the piston in the main cylinder has begun, said cylinders being arranged back to back and their respective piston-rods being connected to the adjacent 70 brake-levers, together with means for locking the piston of the main cylinder against backward movement while the piston of the second cylinder is on its outstroke, said second cylinder being of larger cross-section than the first cylinder.

6. In a fluid-pressure brake system, the combination with the main cylinder, its piston and piston-rod, brake-rigging and triple valve, of a second brake-cylinder, its piston and piston-rod, and means for admitting 75 fluid under pressure to the second cylinder after the movement of the piston in the main cylinder has begun, said cylinders being arranged back to back and their respective piston-rods being connected to the adjacent 80 brake-levers, together with means for locking the piston of the main cylinder against backward movement while the piston of the second cylinder is on its outstroke, said second cylinder being of larger cross-section than the first cylinder.

7. In a fluid-pressure brake system, the combination with the main cylinder, its piston and piston-rod, brake-rigging and triple valve, of a second brake-cylinder, its piston and piston-rod, and means for admitting 85 fluid under pressure to the second cylinder after the movement of the piston in the main cylinder has begun, said cylinders being arranged back to back and their respective piston-rods being connected to the adjacent 90 brake-levers, together with means for locking the piston of the main cylinder against backward movement while the piston of the second cylinder is on its outstroke, and for unlocking it during release of the brakes, said second cylinder being of larger cross-section than the first cylinder.

8. In a fluid-pressure brake system, the combination with the main cylinder, its piston and piston-rod, brake-rigging and triple valve, of a second brake-cylinder, its piston and piston-rod, and means for admitting 95 fluid under pressure to the second cylinder after the movement of the piston in the main cylinder has begun, said cylinders being arranged back to back and their respective piston-rods being connected to the adjacent 100 brake-levers, together with means for locking the piston of the main cylinder against backward movement while the piston of the second cylinder is on its outstroke, and for unlocking it during release of the brakes, said second cylinder being of larger cross-section than the first cylinder.

8. In a fluid-pressure brake system, the

- combination with the main cylinder, its piston and piston-rod, brake-rigging and triple valve, of a second brake-cylinder, its piston and piston-rod, and means for admitting 5 fluid under pressure to the second cylinder after the movement of the piston in the main cylinder has begun, said cylinders being arranged back to back and their respective piston - rods being connected to the adjacent 10 brake-levers, together with means for locking the piston of the main cylinder against backward movement while the piston of the second cylinder is on its outstroke and for unlocking it during release of the brakes, said means 15 comprising a friction-clutch rigidly mounted with reference to the main cylinder, and engaging the piston-rod thereof, and a tripping mechanism actuated by the return stroke of the piston of the second cylinder.
- 20 9. In a fluid-pressure brake system, the combination with the main cylinder, its piston and piston-rod, brake-rigging and triple valve, of a second brake-cylinder, its piston and piston-rod, and means for admitting 25 fluid under pressure to the second cylinder after the movement of the piston in the main cylinder has begun, said cylinders being arranged back to back and their respective piston- rods being connected to the adjacent 30 brake-levers, and the connection of the second piston-rod to the brake-rigging comprising a system of levers for increasing the effective thrust of said piston-rod.
- 35 10. In a fluid-pressure brake system, the combination with the main cylinder, its piston and piston-rod, brake-rigging and triple valve, of a second brake-cylinder, its piston and piston-rod, and means for admitting 40 fluid under pressure to the second cylinder after the movement of the piston in the main cylinder has begun, said cylinders being arranged back to back and their respective piston- rods being connected to the adjacent 45 brake-levers, said means comprising a conduit 50 extending from a port in the side of the first cylinder to the second cylinder and a valve controlling said conduit and adapted to open only upon the attainment of a predetermined fluid-pressure in said conduit.
- 55 11. In a fluid-pressure brake system, the combination with the main cylinder, its piston and piston-rod, brake-rigging and triple valve, of a second brake-cylinder, its piston and piston-rod, and means for admitting 60 fluid under pressure to the second cylinder after the movement of the piston in the main cylinder has begun, said cylinders being arranged back to back and their respective piston- rods being connected to the adjacent 65 brake-levers.
12. In a fluid-pressure brake system, the combination with the main cylinder, its piston and piston-rod, brake-rigging and triple

valve, of a second brake-cylinder, its piston and piston - rod, and means for admitting 65 fluid under pressure to the second cylinder after the movement of the piston in the main cylinder has begun, said cylinders being arranged back to back and their respective piston - rods being connected to the adjacent 70 brake-levers, said second cylinder being of larger cross-section than the first cylinder.

13. In a fluid-pressure brake system, the combination with the main cylinder, its piston and piston-rod, brake-rigging and triple 75 valve, of a second brake-cylinder, its piston and piston-rod, and means for admitting fluid under pressure to the second cylinder after the movement of the piston in the main cylinder has begun, said cylinders being arranged back to back and their respective piston- rods being connected to the adjacent 80 brake-levers, said means comprising a conduit extending from the first cylinder to the second cylinder and a valve controlling said 85 conduit and adapted to open only upon the attainment of a predetermined fluid-pressure in said conduit.

14. In a fluid-pressure brake system, the combination with the two brake-levers and 90 connecting tie-rod of the brake-rigging, of a brake-cylinder and piston operatively connected to one brake-lever, and a second brake-cylinder and piston operatively connected to the second brake-lever, together with means 95 for permitting fluid under pressure to pass from one cylinder to the other after the piston in the first cylinder has traveled a definite portion of its outward stroke, and mechanism for preventing backward movement 100 of the piston in the first cylinder until the discharge of fluid under pressure from the cylinders is begun.

15. In a fluid-pressure brake system, the combination with the two brake-levers and 10 connecting tie-rod of the brake-rigging, of a brake-cylinder and piston operatively connected to one brake-lever, and a second brake-cylinder and piston operatively connected to the second brake-lever, together with means 11 for permitting fluid under pressure to pass from one cylinder to the other after the piston in the first cylinder has traveled a definite portion of its outward stroke, and mechanism for preventing backward movement of the piston in the first cylinder until the discharge of fluid under pressure is begun, said means comprising a passage extending from the end of the second cylinder to a port in the side of the first cylinder.

16. In a fluid-pressure brake system, the combination with the two brake-levers and connecting tie-rod of the brake-rigging, of a brake-cylinder and piston operatively connected to one brake-lever, and a second brake-cylinder and piston operatively connected to

the second brake-lever, together with means for permitting fluid under pressure to pass from one cylinder to the other after the piston in the first cylinder has traveled a definite portion of its outward stroke, and mechanism for preventing backward movement of the piston in the first cylinder until the discharge of fluid under pressure from the cylin-

ders is begun, the second cylinder being of greater cross-section than the first cylinder. 10

Signed at New York, N. Y., this 19th day of December, 1905.
